UNITED STATES PATENT OFFICE.

AUGUST DE KLEIST, OF NORTH TONAWANDA, NEW YORK.

PNEUMATIC ACTION FOR MUSICAL INSTRUMENTS.

1,041,487.

Specification of Letters Patent.

Patented Oct. 15, 1912.

Application filed May 6, 1910. Serial No. 559,824.

To all whom it may concern:

Be it known that I, AUGUST DE KLEIST, a citizen of the United States, residing at North Tonawanda, in the county of Erie and State of New York, have invented new and useful Improvements in Pneumatic Actions for Musical Instruments, of which the following is a specification.

This invention relates to self-playing musical instruments having a pneumatic action which is controlled by the usual perforated music sheet.

One of its objects is to improve the wind chest of the action with a view of simplifying its construction, reducing its cost and rendering it more compact.

A further object is to so construct the wind chest that access can be conveniently had to any of the valves of the pneumatic action without the necessity of dismembering the whole chest; and to construct the chest in sections in such manner that in the event of any of its main parts splitting or otherwise becoming unserviceable, the defective parts can be readily replaced without disturbing or renewing other parts of the chest.

In the accompanying drawings consisting of two sheets: Figure 1 is a transverse section of the wind chest taken through one of the valve chambers. Fig. 2 is a similar section taken through the exhaust conduit or connection of the chest. Fig. 3 is a fragmentary horizontal section on line 3-3, Fig. 1. Fig. 4 is a rear view of the chest with the motor pneumatics shown in section.

Similar letters of reference indicate corresponding parts throughout the several views.

40 The wind chest comprises a main vertical or longitudinal front section A containing an exhaust chamber B which extends throughout the length of the chest, and one or more longitudinal rear sections, valve-boards or 45 bars C secured to the rear side of the front section A, one above another, by screws b or other suitable means.

As shown in the drawings, the main or front section of the chest comprises a front 50 wall a, a rear wall a¹, a top board a², a bottom board or strip a³, and end walls a⁴.

D indicates a tracker board of ordinary construction; and E the customary motor pneumatics, the movable boards of which 55 are connected with the usual abstracts f which actuate the parts of the piano-action

or other sound producing members, not shown in the drawings.

In the preferred construction shown, the valve-boards C are separated to form spaces 60 which receive the front portions of the motor pneumatics, the stationary top boards e of the latter being glued or otherwise secured to the underside of the corresponding valve board. Each of these valve-boards 65 contains a row of valve-chambers g, one for each of the corresponding series of motor pneumatics. As shown in Fig. 1, each motor pneumatic is connected with the corresponding valve chamber by a port h preferably formed in the bottom of the latter. This valve chamber communicates with the outer atmosphere by one or more ports i 70 preferably formed in its rear wall and with the exhaust chamber B by an exhaust port j formed in a plate J which covers the front 75 end of the valve chamber. This plate is screwed or otherwise removably secured to the rear wall a¹ of the exhaust section A of the chest, so as to be readily accessible 80 upon removing the front board a of said section, which latter is secured in place by screws a⁵ or other appropriate fastenings. The air port i and exhaust port j of each 85 valve chamber are controlled by the customary valves k, k¹, both mounted on a stem k² which is guided in the rear portion of the corresponding valve board C and in the plate J. A spring l applied to the valve-stem between the air valve k and an internal 90 shoulder of the valve-board C serves to hold said valves in the normal position shown in Figs. 1 and 3.

The front portion of each valve stem extends into the exhaust chamber B and terminates in the usual button which bears against the pouch or pneumatic m covering a pouch chamber n in the inner side of the pouch-board or removable outer wall a of the wind chest. Leading to each of these 100 pouch-chambers is a channel o which is connected with the corresponding duct p to the tracker-board D by a tube p. As shown in Fig. 1, the channels o are formed partly in the upper portion of the pouch-board a 105 and partly in the top board a² of the wind chest. The rear portions of the valve boards are preferably secured together by cleats q or other suitable means, and the motor-pneumatics of each row may likewise 110 be tied together by a strip or cleat r.

s indicates a suction trunk connected with

the usual main bellows or pump of the instrument, not shown in the drawings, and leading to the exhaust chamber B, as seen in Fig. 2.

5 As the operation of pneumatic actions of this type is well understood, a brief description of the operation of the present one will suffice. In the normal position of the parts, the air valves *k* are open, the exhaust valves *k*¹ are closed and the motor pneumatics are expanded. When a perforation of the music sheet registers with the corresponding tracker duct, the outer atmosphere enters the pouch chamber *n* 10 through the channel *o* and reverses the position of the pouch *m*, thereby opening the exhaust valve and closing the air valve and placing the corresponding motor-pneumatic 15 communication with the exhaust chamber B. The pneumatic is thereby collapsed and caused to actuate the corresponding abstract *f*. When an imperforate portion of the music sheet closes said tracker-duct, the spring *l* returns the exhaust and air valves 20 to their former position, flushing the motor pneumatic and again inflating it in the usual manner.

In order to adjust or regulate the valves of the action, it is only necessary to remove 30 the front or pouch board *a* of the chest, while if it be desired to repair, clean or renew any of the valves, they can be conveniently reached by simply removing said pouch board together with the guide plate 35 *J* of the defective valve, thus affording ready access to the valves without requiring removal of other parts of the chest or the pneumatic action and without disturbing any other parts.

40 In case any of the valve-boards or bars *C* should check or split in the course of time, the defective board can be conveniently unscrewed from the main section *A* of the

chest and repaired or replaced by a new board without the necessity of disturbing 45 or renewing any of the remaining valve boards or other parts, thus materially reducing the cost of such repairs and renewals.

It will be observed that this improved 50 chest comprises comparatively few parts and is exceedingly simple in construction, enabling it to be produced at small cost and to be repaired by ordinary mechanics. It is moreover compact and narrow from front 55 to rear, leaving a correspondingly greater space between it and the piano-action or other sound producing parts of the instrument and permitting more convenient access thereto for adjusting purposes. 60

I claim as my invention:

The combination of a wind chest comprising a section containing an exhaust chamber and having a removable front wall, a plurality of separate valve boards secured to the back of the rear wall of said section and individually removable therefrom, each of said valve boards containing a row of valve chambers extending through 70 said rear wall and communicating with said exhaust chamber, guide plates covering the front ends of said valve chambers and containing exhaust ports, said plates being removably secured to the rear wall of said exhaust chamber, air and exhaust valves in said 75 valve chambers having their stems guided in said removable plates, motor pneumatics connected with said valve chambers, and operating diaphragms for said valves applied to the inner side of said removable front wall, 80

Witness my hand this 3d day of May, 1910.

AUGUST DE KLEIST.
